UNITED STATES PATENT OFFICE.

GEORGE WRAY SMITHSON, OF MADELIA, MINNESOTA.

BUCKLE.

No. 890,462.

Specification of Letters Patent.

Patented June 9, 1908.

Application filed August 5, 1907. Serial No. 387,124.

To all whom it may concern:

Be it known that I, GEORGE WRAY SMITHSON, a citizen of the United States, residing at Madelia, in the county of Watonwan and 5 State of Minnesota, have invented a new and useful Buckle, of which the following is a specification.

This invention relates to harness buckles.

The object of the invention is to provide a 10 novel form of buckle or fastener that will securely connect the outside or main line to the inside or cross line of a double harness, and one in which there will be no points or projections on which a fly net will catch, or which 15 would be liable to inflict injury to the horse, and one in which the draft does not all fall upon the tongue, but is largely taken by clamping the line between parts of the buckle. Furthermore, to provide a buckle having the 20 above characteristics and the added ones of being strong, durable and simple of construction, ready of attachment to the parts with which it coacts, capable of easy adjustment when required, and cheap of production.

25 With the above and other objects in view, as will appear as the nature of the invention is better understood, the same consists in the novel construction and combination of parts of a harness buckle as will be hereinafter 30 fully described and claimed.

In the accompanying drawing forming a part of this specification and in which like characters of reference indicate corresponding parts,—Figure 1 is a view in perspective, 35 displaying the buckle positioned on a part of a harness. Fig. 2 is a longitudinal sectional view through Fig. 1. Fig. 3 is a transverse sectional view taken on the line 3—3 of Fig. 2. Fig. 4 is a view in side elevation, partly 40 in section of a portion of a modified form of buckle. Fig. 5 is a perspective detail view of a modified form of locking tongue. Fig. 6 is a transverse sectional view taken on the line 6—6, Fig. 4.

45 The buckle comprises a frame consisting of two side bars 1 that constitute guides, and two cross bars 2 and 3 that constitute clamps, these parts being integral and cast, or if preferred the article may be drop-forged. The 50 clamps 2 and 3 are connected by a longitudinally and centrally disposed guard 4 that is hollow or channeled on its under side, and may extend throughout the entire length of the buckle or be made somewhat shorter, if 55 such construction should be found advantageous. The guides 1 are obliquely disposed

to the clamps and their edges are engaged by a pair of ears 5 located adjacent to one end of a locking plate 6, the other end of which carries a tongue 7 that is designed to engage either one of a pair of orifices 8 in the clamp 3. The locking plate is preferably resilient, and is somewhat shorter than the length of the frame, in order that when the two straps are locked, as shown in Fig. 2, there will be 60 no projecting portions at the ends of the frame upon which a fly net or the like would be liable to catch.

The ears 5, as stated, bear upon the upper edges of the guides and the coaction between 70 the two causes the plate to approach the plane of the clamps 2 and 3 when draft is applied to the main line L. In order to prevent the ears from presenting protuberances or obstructions that would be liable to catch 75 in a fly net or the like, the buckle shown in Figs. 1, 2 and 3 is provided at its sides with keepers or shields 9 in which the terminals of the ears work, as clearly shown in Fig. 3. These keepers are by preference integral with 80 the side bars and are preferably, although not of necessity, commensurate in width therewith.

The side bars are connected by a cross rod 10 that is designed to be engaged by the 85 cross line L², the latter being looped around the rod and secured as by a rivet 11.

In employing the buckle thus described, the tongue 7 is inserted through any one of the series of openings in the main line, and 90 upon draft being applied to this line in the direction of the arrow shown in Fig. 2, the ears 5 will be caused to ride upon the inclined edges of the guides 1 and thereby lift the locking plate and with it the line so that 95 the latter is firmly clasped between the clamps and the locking plate. This movement of the locking plate will cause the tongue to spring into one or the other of the orifices 8 in the clamp 3 and thereby positively secure the line and buckle together. To disconnect the tongue from the clamp, it will be only necessary to draw down upon that end of the main line at which the tongue 100 is located.

In some instances it may be desired to dispense with the guard 4 and the keepers 9 and this form of the invention is shown in Figs. 4, 5 and 6, wherein the clamp 12 is made somewhat thicker than the clamp 13, and is 110 provided with one or more orifices 14 to receive the tongue 7. The side bars 1 are

channeled in their upper inner sides thereby providing shoulders 15 on the lower inner sides which serve as guides for the ears 16 of the locking plate 17, these latter ears being disposed in the same plane as the body of the locking plate.

It will be seen from the foregoing description that the improvements herein defined are simple in character and may be applied 10 to an existing harness without requiring any change whatever in its structural arrangement.

What is claimed is:—

1. A buckle comprising a frame embodying lateral guides and transverse clamps, one 15 of which is provided with an orifice, and a locking plate having a tongue to engage the orifice and ears to engage the guides.

2. A buckle comprising a pair of clamping 20 members and a pair of guides disposed obliquely thereto, one of the clamping members being provided with a plurality of orifices, and a locking plate having ears to en-

gage with the guides and a tongue to engage the said orifices.

3. A buckle comprising a pair of guides, a 25 pair of clamps connecting the guides, one of the clamps being provided with a plurality of orifices, a guard covering the orifices, and a locking plate having ears to engage with the 30 guides and a tongue to engage the said orifices.

4. A buckle comprising a pair of guides provided with lateral keepers, a pair of 35 clamps connecting the guides one of which is provided with a plurality of orifices, and a locking plate having lateral ears to work within the keepers and a tongue to engage the orifices.

In testimony that I claim the foregoing as my own, I have hereto affixed my signature 40 in the presence of two witnesses.

GEORGE WRAY SMITHSON.
